SPRAYING DEVICE

Alfred Steinke, Harburg-Wilhelmsburg, Germany,
assignor of four-tenths to Francis J. L. Dorl,
New York, N. Y.

Application March 18, 1932, Serial No. 599,634.
Renewed October 25, 1934. In Germany March
19, 1931

6 Claims. (Cl. 91—45)

This invention relates to new and useful improvements in spraying devices and attachments thereto, and it has been the object of this invention to eliminate the atomized cloud of spraying material which usually surrounds the operator and which is extremely injurious to health. A further object of this invention is to provide a means whereby continuous lines of even color can be produced on walls or other objects to be sprayed without the use of stencils. Other objects of my device are to produce patterns of various kinds directly by the use of small stencils inserted in the device, and to return the surplus material to the container without any waste, still other objects will be evident from the following specification and claims.

I attain these objects by the mechanism illustrated in the accompanying drawing, in which:

Fig. 1 shows the device in side elevation, the attachment and color container being shown in section.

Fig. 2 is a plan view of the bracket supporting the attachment and the color container.

Fig. 3 shows a sample of a double line pattern.

Figs. 4 and 5 show different types of stencils.

In Fig. 1, *a* is a nipple for the connection of a compressed air hose, *b* is a nozzle through which the compressed air is forced, a gun handle *c* is attached to the barrel in the usual manner while a valve mechanism with trigger *z* is arranged for shutting off the air when desired. A bracket *e* supports another nozzle *d* from which a tubular connection leads to the color container *f* the neck of which is threaded into bracket *e* which also supports the stencil attachment. This novel attachment consists mainly of a container *g* with two apertures *g*₁ and *g*₂ mounted directly in line with the jet emanating from the nozzle *b*. The nozzle *d* is loosely mounted in tube *d*₁ and turnable in same together with the tubular connection to the color container *f*, this tube having at its lower end a sieve *h* the weight of which always brings the end of the tube to the lowest part of the container *f* by gravitational force.

A screen *i* consisting of a disc with an aperture is mounted in the path of the jet in container *g* in the nozzle of which is further inserted the stencil *k* which is easily removable. This nozzle of the container *g* further supports the roller *r* which is used for guiding the spraygun along the object to be sprayed. The screen *i* has an opening at the bottom permitting surplus material to flow back to the container *f*, through the tube *l*. In Fig. 2, *e* is the bracket into which is threaded the neck of the container *f* so as to be easily dis-

mounted for refilling and cleaning, on the top of this bracket *e* is mounted the container *g* (see Fig. 1) turnable around the tube *l*, a pin *n* rigidly fastened in *e* engages in holes *m* in the container *g*, a screw *g*₃ extends from *g* through slot *g*₄ in bracket *e*. By tightening the nut on *g*₃ the screening container *g* may be adjusted in any desired position indicated by *g*', *g*'' and *g*'''.

In Fig. 3 is shown a typical example of a double line pattern as produced by my invention without the use of suitable stencils *k* in Fig. 1.

In Fig. 4 is shown a sample of pattern produced by a square holed stencil *k*, the lines *k*₁ being produced by rolling the spraygun on roller *r* over the surface to be sprayed.

In Fig. 5 is shown a pattern produced by a circular holed stencil *k*, lines *k*₁ being produced as shown in Fig. 4 while circles *k*₂ are produced by letting the spraygun stand still for a moment.

The operation of my invention is as follows: The compressed air escaping through nozzle *b* sucks the color through nozzle *d* in known manner and produces a jet of spraying material which may be paint, varnish, lacquer, etc. This jet is projected in through the opening *g*₁ in the screening attachment *g* through the aperture in the disc *i*. The thus concentrated jet finally strikes the stencil *k* which being held close to the object to be sprayed produces the desired pattern. Through the fact that the spray passes through a closed container *g* all along its path from the nozzle to the sprayed object no atomized materials can escape to the outside, all such surplus materials being returned to the container *f*. A further feature in the operation of my device is the turnable mounting of the sprayer hood or screening container as mentioned under Fig. 2 above. By this means it is possible as shown in Fig. 3 to produce single lines without the use of any stencil *k*, these lines then become sharply distinguished on one side while the other side is gradually fading away.

Having thus described my invention, what I claim is:—

1. A spraying apparatus of the class described comprising a nozzle connected to a source of fluid pressure, an aspirator nozzle connected to a source of coloring matter and spaced relative to said first nozzle to form a spray of coloring matter, a hood in front of said first nozzle and having a mixing chamber for the spray of color and air forward of said nozzle, said hood having means to interchangeably hold stencils therein, stencil means in said holding means to limit the shape of said color spray, and means on said hood to

facilitate a continuous movement of said apparatus at a relatively fixed distance between the hood and a surface to be decorated.

2. A spraying apparatus of the class described comprising a nozzle connected to a source of fluid pressure, an aspirator nozzle connected to a source of coloring matter and spaced relative to said first nozzle to form a spray of coloring matter, a hood adjacent to and in line with said first nozzle, said hood having means to interchangeably hold stencils therein, stencil means in said holding means to limit the shape of said color spray, means on said hood to facilitate a continuous movement of said apparatus at a relatively fixed distance between the hood and a surface to be decorated, and swivel means between the nozzle and the hood, whereby said aspirator nozzle may be swivelled to one side or the other with respect to said hood so that the concentration of the spray may vary from side to side.

3. A spraying apparatus of the class described comprising a bracket, a spray member pivotally mounted on said bracket, a hood adjacent to and in line with said spray member, said hood having means to interchangeably hold stencils therein, a stencil means in said holding means, a pair of wheels mounted on said hood and projecting beyond the front surface thereof, said wheels adapted to maintain said stencil means at a fixed distance from a surface to be sprayed, and means to pivot said spray member to vary the distance of either edge of the spray to the surface to be decorated.

4. A spraying apparatus of the class described comprising a bracket, a spray member mounted on said bracket, a hood adjacent to and in line with said spray member, said hood having means to interchangeably hold stencils therein, a pair of wheels mounted on said hood and projecting beyond the front surface thereof, said wheels adapted to maintain a suitable distance between a surface to be sprayed and the spray member, said hood having a plate therein, dividing said

hood into an air and spray mixing chamber and a stencil receiving chamber, said plate having a generally central aperture for regulating the spray which is to enter said stencil receiving chamber.

5. A spraying apparatus of the class described comprising a bracket, a spray member pivotally mounted on said bracket, a hood adjacent to and in line with said spray member, said hood having means to interchangeably hold stencils in the front portion thereof, means to maintain a relatively fixed and suitable distance between a surface to be sprayed and the hood member, said hood having an apertured plate therein, dividing said hood into an air and spray mixing chamber and a stencil receiving chamber, and means to swivelably mount said spray member with respect to said hood to shade a stencilled design by varying the concentration of color across the design.

6. A spraying device, comprising in combination, an atomizer for liquids and consisting of a nozzle conveying liquid and a nozzle for compressed air in cooperation, a hood in the direction of the liquid jet issuing from the atomizer and having a mouthpiece opposite to the atomizer, said hood having a spray and air mixing chamber forward of the nozzles, color controlling means adjacent the mouthpiece of the hood in the line of the spray, a carrier holding the atomizer and the hood and adapted to be fixed on a container for the liquid to be sprayed, rollers at the side of the mouthpiece of the hood in such position as to guide the mouthpiece in close proximity over the surface on which the liquid is to be sprayed and an elbowed liquid feeding pipe, the upper part of which is loosely turnable in the liquid nozzle so that the bent lower part of the pipe extending into the liquid container will adjust itself automatically toward the lowest point within the said container when the apparatus is held in an inclined position.

ALFRED STEINKE.
